United States Patent Office

Des. 226,953
Patented May 22, 1973

226,953

HUMIDIFIER

Robert T. Martin, 1708 East 4800 South,
Salt Lake City, Utah 84117

Filed Sept. 2, 1971, Ser. No. 177,541

Term of patent 14 years

Int. Cl. D23—99

U.S. Cl. D23—146

FIG. 1

FIG. 2

FIG. 3

FIG. 4

FIG. 5

FIG. 1 is a perspective view of a humidifier showing my new design;

FIG. 2 is a top view thereof;

FIG. 3 is a bottom view thereof;

FIG. 4 is a side view thereof; and

FIG. 5 is an opposite side view of the humidifier.

I claim:

The ornamental design for a humidifier, as shown.
